UNITED STATES PATENT OFFICE.

WALTER LANGMUIR WATT, OF BRIGHTON, ENGLAND.

GOLF-PRACTICING DEVICE.

Application filed June 13, 1923. Serial No. 645,120.

To all whom it may concern:

Be it known that I, WALTER LANGMUIR WATT, of Brighton, England, a subject of the King of Great Britain and Ireland, have 5 invented certain new and useful Improvements in and Relating to Golf-Practicing Devices, of which the following is a specification.

This invention relates to golf-practicing 10 machines and the like.

The object of the invention is to provide such a machine of a simple and compact construction, and one that is capable of varied adaptation either indoors or outdoors 15 and by right-hand and left-hand players alike, and that will indicate the distance of the hit and its kind, that is to say, for instance, the length of a hit and whether it is a clean one or a mis-hit.

20 To this end, a machine embodying the invention comprises, essentially, a turnable support carrying a spring or springs, or its or their equivalent, associated with a movable member in connection with the 25 playing ball and a recorder, the construction and arrangement being such that when the ball is struck the energy is transmitted to the spring or springs or the equivalent thereof by the movable member, and to the 30 support, which denote the distance the ball is hit and the type of stroke by, respectively, the compression or tension or action of the spring or springs or the equivalent, and the 35 direction or directions in which the support is turned.

I will now describe my invention with reference to the accompanying drawings, whereof:—

Fig. 1 is a diagrammatic perspective view 40 of one form of machine constructed in accordance with it, parts being assumed removed for the sake of clearness; and

Fig. 2 is a corresponding view with the said parts in position.

45 Fig. 3 is a side elevation of another form of machine embodying the invention, a portion being shown in section to illustrate a detail;

Fig. 4 is a broken longitudinal central 50 section thereof on an enlarged scale; and,

Fig. 5 is a corresponding plan.

Fig. 6 is a transverse sectional elevation on the line A—A, Fig. 3; and

55 Fig. 7 is a sectional plan on the line B—B in the same figure.

Figs. 8, 9, and 10 are transverse sectional

elevations, respectively, on the lines C—C, D—D and E—E of Fig. 4.

Figs. 11, 12, 13, and 14 are diagrammatic sectional elevations representing modifications to which I will subsequently refer in detail; and

Fig. 15 is a central section of a playing ball, particularly applicable for use in and with the machine.

65 The same reference numerals are used throughout to designate the same or equivalent parts.

I will first describe the example shown 70 in Figures 1 and 2 according to which I employ a support composed of a base 11 and a standard 12. The base 11 is in the form of a horizontally-disposed flat bar fashioned, intermediate of its ends, to produce a U-shaped portion depending vertically and 75 constituting the standard 12 for giving the requisite elevation of the machine with respect to the ground or floor upon which it is positioned for use, and for effecting its attachment thereto. The attachment is ac- 80 complished by bending or twisting the arched or closed end of the standard 12 and pivoting it at 13 in a fork 14 projecting from a turntable 15, such as a disc revolvably mounted on or in the floor or, as shown, on 85 or in a post 16 bedded in the ground. The maintenance of the horizontal position of the base 11 under normal circumstances is effected by a spring 17 interposed between, and connected to, the standard 12 and the 90 turntable 15.

Therefore, the support is free to turn in the horizontal plane by virtue of the turntable 15, and in the vertical plane by reason of the pivotal connection 13.

95 At each end of the base I fix a rectangular block, one being marked 18 and the other 19. Between these blocks 18 and 19 I situate a rod 20 of circular section, securing its extremities to the respective blocks 18 and 19 100 so that it is firmly supported and held stationary. I provide a movable member 21 on the rod 20, preferably consisting of a block similar to the fixed end blocks 18 and 19. This movable member or block 21 is designed 105 to slide along the rod 20 in either direction and in so doing it may contact with the base 11 whereby its stability or alinement is ensured. Normally, this slidable block 21 is maintained in close proximity to one of the 110 fixed blocks—19 in the example—by a spiral spring 22 freely encircling the rod 20 and

abutting at its contiguous ends against the 5 slidable block 21 and the distant fixed end block 18, the spring 22 being of a type tending always to press the slidable block 21 towards the adjacent end block 19 and, in consequence, oppose its movement towards the complementary or distant block 18.

At the inner face of the fixed end block 18 distant from the slidable block 21, I 10 anchor a spiral spring 23 and mount a pulley 24 horizontally. I also make an opening 25 completely through the block 18. At the corresponding face of the slidable block 21, and at each side of the rod 20 and spring 22, I mount a pulley vertically, 15 one being marked 26 and the other 27. These several parts are for the reception of a flexible connector, such as a cord 28. The cord 28 is, at one end, fastened to the free 20 extremity of the spring 23, and is then passed to and over one, 26, of the pulleys 26 and 27 on the slidable block 21, whence it is led to and around the horizontal pulley 24 at the fixed end block 18, thence to and 25 over the other pulley 27 at the slidable block 21, back to the fixed block 18, and through the opening 25 therein, where it is secured to one ring of a double-ringed 30 swivel 29. To the other ring 30 of the swivel 29 the ball 31 is attached through the medium of a cord 32. The relative arrangement of the swivel 29 and the block-opening 25 is such that the swivel cannot pass through the opening.

35 The rod 20, spring 22 and the allied parts are, as shown in Fig. 2, encased at the top and at one side by a cover 33 connected to, and between, the fixed end blocks 18 and 19, the base 11 forming the bottom closure. The 40 remaining side is partially closed by a flat bar 34 disposed between the fixed blocks 18 and 19 to which it is secured, its depth and position being such that between its upper edge and the top cover 33, and between the base 11 and the lower edge, a slot obtains, 45 these slots being designated 35 and 36 respectively. The outer face of the bar 34 is, as indicated at 37, graduated in linear measure to serve as a component of a recorder, the complement being constituted by a slide or indicator 38 mounted upon the bar 34, its movement being permitted by the slots 35 and 36 just mentioned. The slide or indicator 38 is moved in one, or the recording, direction by the slidable block 21 contacting with it directly, or indirectly through an arm; its return is performed by hand or otherwise independently.

50 Having described the construction of the machine, I will now explain its operation.

Assuming the various components are in the normal position, with the recording slide or indicator 38 at zero, the machine, if required, is turned in the horizontal plane 55 to meet the direction in which it is desired

to make the stroke, and the ball 31 is teed. When the ball 31 is struck, the slidable block 21, through the medium of the interposed cord 28, is drawn along the rod 20 against the action of the spring 22, and 70 simultaneously the slide or indicator 38, through the agency of the block 21, is pushed along its graduated bar 34. On the energy of the ball 31 being exhausted, which has travelled in the direct line of the stroke, 75 the spring 22 re-acts and restores the slidable block 21 to its original position, which likewise returns the ball 31 for the next stroke. The slide or indicator 38 remains in its new position recording the length of 80 the hit, pending its return to zero. In addition to indicating the distance, should, for instance, the stroke be of a character resulting in the ball being sliced, topped, 85 pulled or skied, this will be denoted by a displacement or turning of the machine, horizontally or vertically or both, from the original direction or position.

If the energy of the ball 31 should exceed the resistance offered by the spring 90 22 encompassing the rod, the spring 23 interposed in the cord connection 28 will operate to absorb it. In this case the effect is that of a hammer stroke, and the indicator 38 travels further than the slidable 95 block 21, thus making the record.

From the foregoing it will be manifest that the mere detail construction of a machine incorporating the invention may be modified in sundry ways without, however, departing from its characteristic feature or main essential. This is exemplified in Figs. 3 to 10 inclusive to which I will now refer.

In this example, as in the other, the support comprises a base and a standard. The 105 base, however, is now of a compound structure inasmuch as it is composed of a tubular member 11 and a bar 11^a in spaced relation thereto, instead of a single flat bar. The components 11 and 11^a are each of circular transverse section, and they are united at the ends by the rectangular members or blocks 18 and 19 in the form of plates, the member 11 being let into each, and the member 11^a screwed to each as shown at 11^b and 11^c, respectively, in Figs. 4 and 5. These members 18 and 19 are, in turn, associated with top and bottom covers 33 and 33^a and side covers 34 and 34^a, the whole constituting a hollow oblong structure as clearly 115 shown in Figs. 6, 8, 9 and 10.

The standard 12 is constituted by an upright forked bracket 14 associated with the disc constituting the turntable 15 which is secured to the floor, or a stake, or other base. The basal tube 11 is pivoted at 13 to and between the arms of the bracket 14 forming the standard 12, and the two are connected by the spring 17 maintaining the support in the normal horizontal position. 130

Suitably, the spring 17 is enclosed in a telescopic casing 17^a.

The rod 20, the movable or slidable member 21, and the spring 22 are, in general, 5 constituted and arranged as in the other example, though there are sundry modifications which I will now explain. The most striking modification is that relative to the spring 22, consequently I will refer to it 10 first. As is illustrated in Figures 4 and 5, the spring 22 is not of the simple kind adopted in the other machine represented in Figures 1 and 2, but is of a compound type inasmuch as it consists of two separate elements disposed to the right and the left of a common interposed abutment 21^c slidable on the rod 20 in unison with the member 21 which, relatively, may be termed the primary member. The distant ends of the two-part 15 spring 22 bear as before against the member 21 in the case of the right hand portion, and the end block 18 in the case of the left hand portion. This left hand portion is shorter and stronger than its complementary portion, thereby operating as a 20 buffer to it in the case of full shots. This two-part structure of the spring 22 also tends to obviate binding or buckling when complete, or approximately complete, compression obtains.

The rod 20 is secured to each of the end members 18 and 19 by a screw 20^a. The rod 20 is, with advantage, provided with a longitudinal slot in which is positioned a 25 more or less co-extensive flat spring for contacting with the inner periphery of the two parts of the spring 22. This arrangement, which is represented at 20^b in Figure 9, presents a useful resistance, control or 30 retardation to the compression of the spring 22, as well as to the succeeding extension thereof, thus slowing or cushioning the speed of rebound of the ball 31.

The member 21 is in the form of a block, 45 and is provided with a forked arm 21^a designed to embrace the basal member 11^a; thus the member 21 is effectually stabilized in its reciprocation. The chief function of this arm 21^a, however, is to operate the 50 pointer 38 which projects through the slot 35 in the cover 34 from a boss 38^a slidably mounted on the basal member 11^a. The graduations complementary to the pointer 38 are provided on a strip 37 secured to 55 the cover 34 above the slot 35, therein. Preferably, the face of the member 21 bearing upon the rod 20, and the like face of the boss 38^a of the pointer 38 contacting with the basal member 11^a, is provided with 60 a slot in which a flat spring is disposed. Such device, in the case of the pointer, is illustrated at 38^b in Figure 9, and from it the application to the member 21 will be apparent. The device is a well-known resistance or retarding expedient, and as 65

such it functions in connection with the member 21 and the pointer 38 so as to ensure uniform operation. In the case of the member 21, it is desirable to, as it were, cut out the resistance as the member approaches 70 the end of its return movement so as to permit the cord 28, with the attached ball 31, to return completely home, and to meet this the end of the rod 20 adjacent the member 19 is flattened or reduced in diameter for a 75 convenient distance to render the resistance spring of non-effect.

The member 21 carries two pulleys 26 and 27 as before, but now they are disposed horizontally instead of vertically, and each 80 is housed in a casing 21^b which preserves the position of the cord 28. The complementary pulley 24 is situated at the end block 18, and is also furnished with a housing 24^a, but, as compared with that of the other example, it is arranged vertically and not horizontally. The cord 28 is assembled with these pulleys 24, 26 and 27, spring 23, aperture 25, swivel 29, swivel eyes 28^a and 30, ball 31 and cord 32 as in the other 85 construction of machine.

The resistance device described with reference to the member 21 may be substituted by a device associated with either or both of the pulleys 26 and 27. This device may be on the dash-pot principle comprising a perforated casing applied to the pulley and enclosing a paddle operable by the pulley or its axle to control inlet and outlet of air to and from the casing.

Alternatively, the device may take the form represented in Fig. 11 or in Fig. 12 to which I will now refer.

According to the construction shown in Fig. 11, the pulley, for instance pulley 26, and its axle 26^a are revolvably mounted and supported by the housing 21^b and a casing 39 formed integral with the housing or otherwise. The axle 26^a carries an arm or paddle 40 which co-operates with loose shot 41 contained in the casing 39. The axle 26^a may, according to the arrangement illustrated in Fig. 12, be fixed and only the pulley 26 adapted to revolve, in which case the arm or paddle 40 is secured to the side 105 of the pulley through the agency of an arm 42 which works in a slot 43 in the side of the casing 39. The width of the slot 43 is such as to prevent the escape of the shot 41. In each case, however, as the pulley 26 110 is revolved in either direction under the influence of the cord 28, the paddle 40 displaces the shot 41, and thus the required resistance obtains.

Instead of the pulleys 24, 26 and 27 being 115 separate as explained and illustrated, they may be constructed in one piece so as to constitute a unit as represented in Fig. 13, the arrangement of the allied parts being correspondingly modified. The pulley 24 is 120 125 130

centrally situated and is of a larger diameter than the pulleys 26 and 27. The unit is revolvably mounted on and at the end member 18. The cord 28 is divided, and the respective ends are attached to the pulleys 26 and 27 and the movable member 21, the cord being designed to wind on and unwind from the pulleys 26 and 27. The cord 32 of the ball 31 is similarly associated with the pulley 24, in repose it is wound upon the pulley. Therefore, when the ball 31 is hit the cord 32 is unwound and rotates the pulley 24, whereupon the pulleys 26 and 27 revolve and wind up the divided cord 28 with the result that, as before, the movable member 21 is moved in opposition to the spring 22 to record the distance of the hit.

Instead of the movable member 21 and spring 22 being assembled as described, the arrangement represented in Fig. 14 may be adopted. Here the spring 22 is replaced by a spring 22^a which is secured at one extremity to the end member 18, and at the other extremity to a cord 44 led to and over a pulley 45 supported at and by the end member 19, and finally connected to the movable member 21. The member 21, which slides over the rod 20 as before, is associated with the cord and pulley arrangement described with reference to Fig. 13. When the ball 31 is hit, the member 21 moves outwards against the spring 22^a which returns it, all as before.

The lubrication of the spring 22 and other necessary parts may be attained in any customary manner. For instance, a slide-controlled inlet or inlets may be provided as and where required in any of the covers 33, 33^a, 34 and 34^a, or, alternatively, the rods 11^a and 20 may be replaced by tubes plugged at the ends and perforated at intervals along their length for the reception and discharge of lubricant supplied to a cup fitted at one or both of their ends.

In a modification, the base 11 may be pivoted directly to the turntable which, in turn, is secured to a block or pillar fixed to the floor or sunk in the ground, and of a height presenting the necessary elevation or altitude.

Again, instead of the base 11, blocks 18 and 19, and covers 33, 33^a, 34 and 34^a being as a whole, of a rectangular transverse section, they may be constructed to give a circular tubular section, a segmental portion being graduated and slotted to accommodate the recording slide or indicator 38.

The ball 31 may be secured to the cord 32 in sundry ways. One appropriate way is illustrated in Fig. 15 which comprehends a specially-manufactured ball of standard weight. This ball comprises the golf-ball proper 46 of an ordinary type, but of re-

duced diameter and weight as compared with the standard ball, and an enclosing 65 casing 47 therefor of gutta-percha or other material. Between the ball 46 and the casing 47 a tape 48 of strong and durable material, such as leather, is interposed and its two ends drawn together and led to the exterior of the casing 47 where they are looped as indicated at 49 to receive the cord 28.

In a further modification, the spring 23, in the construction shown in Fig. 1, instead of being connected to the cord 28 may be attached to the adjacent end of the spring 22 through the medium of a collar, such as 21^c in Figs. 4 and 5, whereby the spring 23 comes in operation more or less simultaneously with the spring 22, whereby a longer recording operation of the indicator 38 accrues because the spring 22 can be shortened in length.

What I claim and desire to secure by Letters Patent is:—

1. A device of the class described comprising a support, a frame carried thereby, means between the frame and the support for permitting the frame to swing both horizontally and vertically, an elastic device carried by the frame and a ball attached thereto for the purpose described.

2. A device of the class described comprising a support, a frame carried thereby and provided with means permitting the frame to swing horizontally or vertically, an elastic device attached to one end of the frame, a ball attached to said elastic device, and an indicator carried by the frame with connections cooperative with the elastic device to indicate the force of a stroke.

3. A golf practicing device comprising a support, a frame carried thereby, a rod carried by the frame, fixed end members on the frame, a member slidable on the rod, a spring encircling the rod and abutting at its opposite ends against the slidable member and a fixed end member, a flexible connector operatively connected with the slidable member, and a ball attached to the flexible connector for the purpose described.

4. A golf practicing device comprising a support consisting of a standard mounted on a turn table, a frame pivotally connected to the standard, end members on the frame carrying a rod, a member slidable over the rod, a spring encircling the rod and abutting at its contiguous ends against the slidable member and an end member, pulleys on the frame, a ball, and a flexible connector extending around the pulleys and connected at one end to an end member and at its opposite end to the ball as described.

In testimony whereof I affix my signature.
WALTER LANGMUIR WATT.
